UNITED STATES PATENT OFFICE.

ELLIS GRANT EDMONSON, OF GREENFIELD, OHIO, ASSIGNOR TO THE AMERICAN PAD & TEXTILE COMPANY, OF GREENFIELD, OHIO, A CORPORATION OF OHIO.

SACK-TURNING MECHANISM.

1,172,443.

Specification of Letters Patent. Patented Feb. 22, 1916.

Application filed December 5, 1914, Serial No. 875,673. Renewed January 7, 1916. Serial No. 70,886.

To all whom it may concern:

Be it known that I, ELLIS G. EDMONSON, a citizen of the United States, residing at Greenfield, in the county of Highland and State of Ohio, have invented certain new and useful Improvements in Sack-Turning Mechanism, of which the following is a specification, reference being had to the accompanying drawings.

10 My invention relates to devices whereby sacks or bags may be turned inside out and the object of my invention is the provision of a mechanism of this character of great simplicity, easily operated, and thoroughly effective in use.

15 A further object of the invention is to provide a device which will engage the bottom or inverted end of a bag so as to permit the open lower end of the inverted bag to be drawn upward, thus turning the bag inside out.

20 A further object is to provide means whereby the bag engaging members may be readily contracted so as to invert a bag upon them and when released that they shall automatically engage the upper bottom end of the inverted bag.

25 Other objects will appear in the course of the following description.

30 My invention is illustrated in the accompanying drawings wherein—

Figure 1 is an elevation of my bag turning mechanism partly broken away; Fig. 2 is a fragmentary plan view of the table 35 upon which the device is mounted; Fig. 3 is a detail elevation of the bar applied to the arms for the purpose of holding bags of relatively great width.

Referring to these drawings, 2 designates 40 a table, platform or other operative base, this table being supported by the legs 3. Mounted upon the table or base is a base plate 4 of any suitable construction, and mounted upon this base plate are the upwardly extending spaced bag engaging standards 5. These standards are illustrated as being angularly turned at their lower ends as at 6 and rigidly fastened to the base plate. The standards have a certain degree of resiliency so that the upper 45 ends of the standards may be moved closer together or farther apart as desired to adjust the device to different sizes of bags. For the purpose of limiting the outward 50 movement of the standards, I provide a 55 turn buckle 7, one end of which has swiveled engagement with a pin or like member 8, while the other end has screw threaded engagement with a screw threaded pin 9. The pin 8 projects from one of the standards 5, 60 and the pin 9 from the other. It will thus be obvious that by rotating the turn buckle, the standards may be drawn closer together and that the turn buckle permits the standards to be freely shifted closer together but 65 limits the outward movement of the standards.

For the purpose of forcing the bag supports outward, I provide a compression 70 spring 10 which is disposed between the standards and which is supported by means of the inwardly directed pins 11. This compression spring forces the standards outward or apart from each other at their upper ends.

For the purpose of providing means whereby the standards may be manually shifted toward each other in order to permit of the insertion of a bag over the upper 75 ends of the bag supporting standards, I 80 provide the cables 12. Each of these cables at its lower end is attached to an actuating lever 13. The cables pass upwardly from the actuating lever in divergent relation parallel to the standards and at their upper 85 ends pass over pulleys 14. The cables are then crossed and connected each to a pin 16 or like device projecting from one of the standards. A lever 13 is pivoted at one end upon one of the legs 3, and at its other end 90 passes through a guide formed by a plate 17, the inner edge of which is toothed as at 18 to engage the lever, the lever being provided with a handle whereby it may be actuated. It will be obvious now that when the lever 95 is depressed, the upper ends of the bag supporting standards will be drawn toward each other, and that when the lever is released, the upper ends of the bag supporting standards will be forced away from each 100 other by means of the spring 10. The upper end of each standard is formed with a bulbous portion 19 and a relatively small tip 20. Where sacks or bags of very large 105 width are to be turned, I use an auxiliary sack supporting bar designated 21 whose ends are angularly bent as at 22 to secure a good bearing upon the inner ends of the

sack, this bar being provided with openings or sockets 23 for the reception of the tips 20 on the arms or standards 5.

One manner of operating my device, is as follows:—In turning a sack, the operator takes hold of the sack at the mouth with the thumb and forefinger of each hand. He then places the sack with its closed end on the standards and pulls downward on the sack. As the mouth of the sack is pulled downwardly, the closed end of the sack is moved relatively through the open end of the sack. The sack is then turned inside out and may be withdrawn from the standards. By operating the handle 13, the standards may be adjusted for different widths of sacks. By adjusting this handle, the upper ends of the standards may be drawn closer together or allowed to separate to a greater extent for this purpose. The bulbs 19 on the upper ends of the standards prevent the seams on the sack from ripping or tearing. The handle 13 may be used to adjust the standards from four to eighteen inches from each other. For a greater width of sack the bar 21 is intended to be used. The turn buckle 7 is to be used when the bar 21 is disposed upon the standards. The rotation of the turn buckle 7 in one direction shifts the standards so that they are wider apart at the top. This is necessary where the spring 10 is not sufficiently expansive to secure this effect.

Another method of operating my invention may be used. In this, assuming that the arms or standards 5 have been adjusted by means of the turn buckle so as to limit the extent of their maximum separation, then upon a depression of the lever 13, the arms or standards will be drawn toward each other and the bag is inverted over these arms or standards and drawn downward until the bottom of the bag is engaged by the tips 20 and the bulbous portions 19. The lever 13 is then released whereupon the spring 10 will force the arms outward and this will act to spread the bottom of the bag, which is at the top in this case of course, and clamp the bag tightly at its bottom wall. The depending free edge of the bag is then grasped by the hands of the operator and drawn upward and thus the bag is turned inside out. This operation may be very quickly accomplished and the device is particularly of value where relatively big bags are to be turned. When the size of the sacks or bags being turned changes, the turn buckle 7 is adjusted so as to limit the extent of the greatest separation of the bag engaging members, and the same operation is performed. Where bags of great width are to be turned, then the bar 21 is used.

This device is adapted to be used in turning salt sacks, cotton flour sacks, sacks holding grain, baggings, and sweat pad casings,

and for the turning inside out of any like articles. By reason of the fact that the arms or standards 5 converge downward, the lower edge of the sack is entirely free so that the lower edge may be readily turned upward to cause the turning of the sack. 70

Having described my invention, what I claim is:

1. In a sack turning mechanism, a base, outwardly extending, approximately parallel sack engaging members mounted upon the base, the outer ends of said members being movable toward each other, a spring urging the outer ends of the members away from each other, manually operable means 75 for drawing the outer ends of said members toward each other, whereby to adjust the distance between the outer ends of said sack engaging members, and means for adjustably limiting the outward movement of the 85 sack engaging members.

2. In a sack turning mechanism, a base, upwardly extending diverging sack engaging members, a spring urging said members apart, a lever mounted below the base, cables 90 extending upward from the lever, pulleys mounted on the members and from which said cables pass, said cables being crossed after passing over the pulleys and being attached to the respective members, and a turn 95 buckle limiting the outward movement of the members but permitting the movement toward each other.

3. In a sack turning mechanism, a pair of sack holding members supported at one end 100 and the free ends of each being movable toward each other, springs forcing said members apart, manually operable means for drawing said members toward each other, and a sack engaging bar removably mounted 105 on the extremities of said members and having ends adapted to engage the bottom of a sack.

4. In a sack turning mechanism, upwardly extending sack engaging members, over 110 which a sack is adapted to be inverted, and manually controllable means for adjusting the distance between the upper ends of said sack engaging members, said means including an adjustable, manually operable lever 115 and means for holding the lever in a plurality of adjusted positions.

5. In a sack turning machine, a base, outwardly extending sack engaging members, a spring urging the outer ends of said members apart, a lever mounted below the base, cables extending from the lever and operatively connected to the members to cause the members to move toward each other upon a pull upon the cables, and means adjustably limiting the outward movement of the members but permitting their movement toward each other. 125

6. In a sack turning machine, a table forming a supporting base and provided 130

with an opening in its top, upwardly extending divergent yieldingly supported sack engaging members mounted upon the top of the table, a spring urging the outer 5 ends of said members apart, a lever mounted below the table, operative connections between the said lever and said sack engaging members passing through the opening of the top whereby to cause the members to move 10 toward each other upon a predetermined movement of the lever, and means for holding the lever in adjusted positions.

7. In a sack turning machine, a table forming a base, the top of the table having an opening, oppositely disposed upwardly extending divergent sack engaging members

yieldingly supported upon the table, pulleys carried by said members, cables attached each at its upper end to one of said members, the cables then being crossed after 20 passing over said pulleys and extending down through the opening of the table, a lever operatively connected to the cables, and a spring urging the upper ends of said members apart.

25 In testimony whereof I hereunto affix my signature in the presence of two witnesses.
